CLAIM

The ornamental design for an airflow friction reducer for
watercrafts, as shown and described.

DESCRIPTION

FIG. 1 is a rear perspective view of an air flow friction
reducer for watercrafts showing our new design;
FIG. 2 is a front perspective view thereof;
FIG. 3 is a bottom plan view thereof;
FIG. 4 is a top plan view thereof;
FIG. 5 is a bottom perspective view thereof;
FIG. 6 is a top perspective view thereof; and,
FIG. 7 is an exploded perspective view.
